GAME MISSILE AND PROJECTOR THEREFOR

Gabriel J. Lopez, 1500 N. Wood St.,
Chicago, Ill. 60622Filed Sept. 1, 1965, Ser. No. 485,674
6 Claims. (Cl. 273—95)

The present invention relates to games of skill of the type wherein an object is propelled toward a target.

It is an objective of the present invention to provide a novel game of skill wherein an unusually shaped missile is propelled toward a net or other target in a trajectory which is controlled by the player. It is an additional object of the invention to provide such a game wherein a high degree of proficiency may be developed in controlled propulsion of the missile from a platform toward the target.

Other objects and advantages of the invention will be appreciated from a reading of the detailed description provided hereinafter when taken in conjunction with the drawing, wherein:

FIG. 1 is a side elevation of apparatus comprising the present invention;

FIG. 2 is an enlarged partial perspective of the missile, platform and a portion of the hammer and guide which encompasses the present invention;

FIG. 3 is a perspective of an exemplary missile; and

FIG. 4 is a modified form of the invention.

While the invention is susceptible of various modifications and alternative constructions, certain illustrative embodiments have been shown in the drawings and will be described below in considerable detail. It should be understood, however, that there is no intention to limit the invention to the specific forms disclosed, but, on the contrary, the intention is to cover all modifications, alternative constructions and equivalents falling within the spirit and scope of the invention as expressed in the appended claims.

Referring now to the drawings, and more particularly to FIG. 1, apparatus comprising the present invention is illustrated therein, and bears the identifying character 10. In the FIG. 1 embodiment, a propulsion unit 12 is constructed to forcibly hurl a missile 14 through the air towards a net 16, or other target. As illustrated, the net may be connected directly to the propulsion apparatus where two or more players may then aim at each others goal. The target may also be located in any other convenient place without departing from the invention.

The missile 14, in accordance with the invention, is of novel construction, and comprises a generally cylindrical body portion 20 having at least one tapered end portion 22. Referring specifically to FIG. 3, there is illustrated a missile 14 having both ends tapered. It will be appreciated, however, for the purpose of the invention, that as long as one end is tapered as at 22, the other end may be blunt, or take on any other appropriate decorative form. The tapered end 22 resembles a conic section, and the missile may be formed either of wood or any appropriate like metallic substance sufficiently hard to withstand repeated blows as will appear. It will, of course, lend itself to a variety of decorative color codings to distinguish the various players missiles, as well as other appropriate markings which will lend to the individual nature of the missile itself.

In practicing the invention, the missile is forcibly propelled towards the target 16 by applying a sharp blow to the end section 22 of the missile. This, in accordance with the invention, is accomplished by means of a hammer 25 having an end 27 which may be tapered or bevelled somewhat in order to increase the amount of area of the base of the hammer which will contact the missile 22,

thereby decreasing wear on the hammer. The end 27 is an integral part of an elongated shaft having a handle portion 29 attached thereto. The handle portion is provided simply for convenient gripping of the hammer in order that the force, which is applied by hand in this embodiment, may be readily directed as desired.

The hammer 25 rides in any suitable guide or enclosure 32, which, as seen in FIG. 2, in this instance comprises a simple enclosure defining a channel 34 in which the hammer rides. The channel is so constructed to permit free longitudinal movement with sufficient play to permit easy operation, thereby to serve as a convenient guide in order that the forces to be applied against the missile will be properly directed.

Referring specifically to FIG. 2, the missile itself is disposed upon a pad 37 which is recessed as at 39 so as to receive the missile, holding the same in a substantially horizontal position, with slightly less than half of the missile itself being seated within the confines of the recess 39. This may be readily viewed in FIG. 1 where the missile is shown in place on the pad. The pad itself may be integrally formed with, or be fastened to, the base member 42 which supports the guide 32. In the FIG. 1 embodiment, for example, the pad 37 is shown as formed separately from, and thereafter attached to, the base 42 in any convenient fashion such as glueing. In the FIG. 2 embodiment, the pad is integral with the base. From the standpoint of manufacture, the enclosure, the hammer, and the base and pad may all be made of wood, or metal, as practical considerations dictate.

The base, immediately below the enclosure 34, is notched, as at 45. This permits the hammer to pass downward beyond the tapered end 22 of the missile. Thus, the force generated by the hammer against the missile will cause the hammer to pass through the space occupied by the nose of the missile, so as to apply a blow on a line through the axis of the missile, causing the same to hurl end-over-end through the air towards the target 16. It will also be appreciated that, by adjusting the shape of the recess 39 in the pad, the axis of the missile 14 may be tilted slightly downward, or upward, whichever proves most satisfactory, thereby changing the trajectory of flight of the missile.

In order to permit optimum variation of the missile trajectory, the guide is, in accordance with the invention, mounted to the base by means of a conventional spring hinge indicated generally at 50. The hinge (see FIG. 2) comprises a pair of hinge members 52, fastened to the base, and 54, fastened to the guide 32. A hinge pin 56 mounts a coil spring 58 adapted to apply force against the hinge members 52 and 54, to bias them apart. FIG. 1 is illustrative of the use of the hinge 50, and shows that the force to be applied against the missile by the hammer may be applied at various angles. I have found, through use, that control of the missile is especially good between 15° on either side of a 60° angle of attack.

As seen in FIG. 2, the base 60 of the guide member 32 is bevelled, so that the bias of the spring 58 will normally cause the base to seat against the platform portion of the device. This might be constructed to provide a 75° angle between the hammer and base, as indicated in FIG. 1. In order to get more or less distance on the missile travel, the angle may be varied in accordance with the skill of the operator to hit the target.

FIG. 4 is illustrative of another embodiment of the present invention, wherein the foot, rather than the hand, might be used to apply the necessary force for propelling the missile. Thus, a missile 114 which is adapted to be struck by a hammer 125 which resides in a guide member 132 defining a channel 134 therein, and is freely movable in the channel. In this instance, however, the

channel extends only through the lower portion of the enclosure. Further, the enclosure is slotted at the back as at 136, and a foot pedal 138 is connected directly to the hammer 125 which rides in the channel 134. The hammer 125 is of substantially identical construction as that previously described, with the exception that it does not have the grips for hand operation. Instead, the foot pedal 138 is provided. In order to return the hammer to its cocked position above the missile, as illustrated in FIG. 4, there is provided a suitable coil spring 140 which is attached to a part of the guide 132, such as block 142.

The missile 114 seats on a pad 137 attached to or made integrally a part of a base member 142 which mounts the enclosure 132 by means of a suitable hinge 150. As previously indicated, the hinge may be spring loaded, or may provide a permanent attachment, depending upon whether a more economical version of the apparatus is desired. Again, the missile is propelled by being struck by the hammer 125, in this instance through pressure applied by the player's foot to the pedal 138.

An additional feature of the invention, as illustrated in the FIG. 4 embodiment, is the provision of a reload chute 160. This may consist of any suitable tubular member, conveniently formed of plastic or other suitable material, and being bevelled at its lower end 162 so that missiles stacked in the reload chute or passed through the reload chute, will drop from the chute and seat on the pad 137 in position to be struck by the hammer member 125.

Also seen in FIG. 1, is a pin 165 extending upward from the base member 142, and having missiles spindled thereon. Each missile may be formed with a suitable small hole in the body portion 20 thereof, so that they may be placed on the spindle where a player may conveniently reach them.

It will now be apparent that the apparatus disclosed is capable of providing great enjoyment for any number of players, and, while relatively simple to operate, provides sufficient appeal, and optional positions of operation, to permit the development of substantial skill in its operation and use, by increasing enjoyment to be attained from the manipulation thereof.

I claim as my invention:

1. A game of skill comprising a base member having disposed thereon an elongated guide extending upwardly from said base member, a pad on said base member adjacent said elongated guide, a missile on said pad, said missile having a tapered end portion, said guide defining a channel and being open at the end thereof adjacent

said pad, a hammer disposed in said channel for movement longitudinally thereof, the tapered end of said missile protruding into said channel through the opening therein so as to be strikable with said hammer to cause said missile to be propelled from said pad toward a target and means for moving said hammer.

2. A game as set forth in claim 1 wherein said guide is hinged to said base and movable with respect said pad so as to change the angle at which said hammer strikes said missile.

3. A game as set forth in claim 2 wherein means is provided with said hinge for biasing said guide toward a position perpendicular with said base.

4. A game as set forth in claim 1 wherein said pad is formed with a recess therein so as to receive said missile partially within said recess for holding the same at a predetermined attitude with respect to said base.

5. A game as set forth in claim 3 wherein a chute is mounted to said guide, and having the end thereof adjacent said pad and tapered so as to guide missiles in said chute into position on said pad.

6. A game of skill comprising a base member having disposed thereon an elongated guide extending upwardly from said base member, a pad on said base member adjacent said elongated guide, a missile on said pad, said missile having a tapered end portion, said guide defining a channel and being open at the end thereof adjacent said pad, a hammer disposed in said channel for movement longitudinally thereof, a return spring connecting said hammer with said guide, the tapered end of said missile protruding into said channel through the opening therein so as to be strikable with said hammer and a pedal on said hammer adapted to be pushed by a player for moving said hammer against said missile against the bias of said return spring to cause said missile to be propelled from said pad toward a target.
